UNITED STATES PATENT OFFICE.

ALVA J. FISHER, OF CHICAGO, ILLINOIS.

CHAPLET FOR SAND CORES.

SPECIFICATION forming part of Letters Patent No. 404,187, dated May 28, 1889.

Application filed September 28, 1888. Serial No. 286,673. (No model.)

To all whom it may concern:

Be it known that I, ALVA J. FISHER, residing at Chicago, in the county of Cook and State of Illinois, and a citizen of the United States, have invented a new, useful, and Improved Chaplet for Sand Cores, of which the following is a specification, reference being had to the accompanying drawings, in which—

Figure 1 is a vertical section of a flask used in casting car-wheels. Fig. 2 is an under view of the upper section of the flask. Fig. 3 is an elevation of a chaplet, full size. Figs. 1 and 2 are more particularly designed to show the method of using chaplets.

Chaplets as heretofore used have been made of iron, and as they are used in casting car-wheels for the purpose of preventing the sand cores from floating they remain in the wheel. Iron chaplets are subject to several objections or difficulties, as, owing to the mass of molten metal used in casting car-wheels, they are liable to be melted or partly melted, so as to leave the metal of the wheel thinner on one side of the coring, or to entirely ruin the casting. They are also liable to chill the iron around them sufficiently to form starting-points for checks and cracks.

The object of my invention is to overcome these difficulties in using iron chaplets, which I accomplish by making my chaplets of compressed or solidified carbon, which do not melt or weaken under high heat, which do not chill the iron, and which do not become loose or work out of the finished wheel.

In the drawings, *a b* indicate the upper and lower portions of a flask. *a'* are the ribs or radial bars of the upper section, which are ordinarily closer together and more numerous than shown in Fig. 2. *c* indicates the usual iron ring or annulus used for chilling the tread of the wheel. *d* is a car-wheel.

e is the sand core.

f is the under support.

g are holes for inserting the necks of the chaplets.

h is a chaplet having a swell, *h'*, and a shoulder, *h²*, which rests against the frame or skeleton of the upper section of the flask, as shown in Fig. 1.

50

i is the molding-sand.

j is the hub-core.

The flask and the manner of molding car-wheels form no part of my invention, and as they are well known further description is not deemed necessary or essential. The chaplets are placed in the holes *g* of the flask-top, and project therefrom a length equal to the desired thickness of the metal. The oppositely-inclined swell *h'* prevents the chaplet from 60 coming out of the finished wheel. These chaplets can be manufactured of carbon—such as is used in the manufacture of points for electric lamps—and in substantially the same manner, and be dealt with as a separate article 65 of manufacture. Chaplets so made, as I have determined by actual use, are of great advantage in the casting of car-wheels, as by their use defective or imperfect wheels rarely occur, whereas before they were of such frequent 70 occurrence as to materially increase the cost of the manufacture of perfect wheels.

What I claim as new, and desire to secure by Letters Patent, is—

1. As a new article of manufacture, a chaplet composed of solid carbon, substantially as described.

2. A chaplet composed of solid carbon and having a shoulder, *h²*, and oppositely-inclined swell *h'*, substantially as described.

ALVA J. FISHER.
